(30) **Foreign Application Priority Data**

The ornamental design for a sterilizer, as shown and described.

Sep. 4, 2009 (WO) 511727501

DESCRIPTION

(51) **LOC (9) Cl.** **24-01**

FIG. 1 is a first perspective view of a sterilizer of the present design;

(52) **U.S. Cl.** **D24/217**

FIG. 2 is a second perspective view thereof;

(58) **Field of Classification Search** D24/216-218;

FIG. 3 is a front view thereof;

D7/326; 422/24, 26, 27, 307; 206/207, 209,

FIG. 4 is a back view thereof;

206/5.1; 250/455.11; 219/521

FIG. 5 is a right side view thereof;

See application file for complete search history.

FIG. 6 is a left side view thereof;

(56) **References Cited**

FIG. 7 is a top view thereof; and,

U.S. PATENT DOCUMENTS

FIG. 8 is a bottom view thereof.
